UNITED STATES PATENT OFFICE.

WILLIAM N. JAY, OF CLEVELAND, OHIO.

GAME AND APPARATUS THEREFOR.

Application filed April 4, 1923. Serial No. 629,773.

To all whom it may concern:

Be it known that I, WILLIAM N. JAY, a citizen of the United States, residing at Cleveland, in the county of Cuyahoga and State of Ohio, have invented a certain new and useful Improvement in a Game and Apparatus Therefor, of which the following is a full, clear, and exact description, reference being had to the accompanying drawings.

This invention relates to that type of games wherein a striking object is thrown at an object piece from a predetermined distance, such for example, as the game of quoits or horseshoes.

An objection to the game of horseshoes is that when only two players are engaged in the game, each is compelled to traverse the length of the court after each pitching operation. Moreover in such games, the skill of the player is offset by the character of the ground on which the game is played, in that the pitching pieces are frequently deflected from the stake even though the aim of the player is accurate.

One of the objects of my invention therefore, is the provision of a game wherein the skill of a player in striking the stake is rewarded and wherein the objectionable features of having each player traverse the length of the court during play is obviated.

I carry out the above objects by providing a pair of spaced object pieces which are free to move when struck by the pitching piece and which are so spaced that the pitching piece cannot pass between them in one position without striking the object pieces, but can pass between them in another position without striking them. Two of such object pieces are positioned at each end of the court so that each player sets up the object pieces for the other player who remains at the opposite end of the court.

The means for carrying out the objects of my invention will be hereinafter fully described in connection with the accompanying drawings and the essential features will be summarized in the claims.

In the drawings, Fig. 1 represents diagrammatically a court having object pieces arranged according to my invention and positioned at each end of the court; Fig. 2 is an elevation of the object pieces in the

position for play and showing the relation of the object pieces to the pitching piece; 55 Figs. 3 and 4 are plan and side elevations respectively of the pitching piece.

In the drawings, 9 indicates a court at opposite ends of which the object pieces used in my invention are placed. As shown, the 60 object pieces are represented at 10 and 11 and comprise self-sustaining upright members which are spaced a predetermined distance apart. The apparatus illustrated is intended for outdoor use wherein metallic 65 pitching pieces 12 are employed, and accordingly each object piece may comprise a wooden block having metallic facings 13 and 14 on opposite sides thereof respectively.

To position the object pieces at uniform 70 distances apart and at the same time to provide an even bearing for maintaining them in upright position, I have shown a templet 15 which is adapted to rest upon the ground and to have openings therein through which 75 ground-engaging members 16 and 17 may extend. These members as shown are provided with heads 18 and 19 respectively, above the templet, upon which the object pieces are placed. 80

The pitching piece 12 is shown as a metallic disc having a notch 20 which provides a finger grip for the player. The diameter of this disc then determines the distance between the object pieces. As shown in Fig. 2, 85 the diameter of the disc is such that the disc when in substantially horizontal position cannot be passed between the object pieces without striking them, but while in vertical position can readily pass through the opening between the discs without striking them. 90

One player at one end of the court is provided with two or more pitching pieces. As the object pieces at each end of the court are struck and displaced from the original 95 position, the player at that end of the court replaces the object pieces until all of the pitching pieces have been thrown. Thereupon the second player throws the same 100 pitching pieces toward the opposite end of the court while the first player in turn sets up the object pieces.

While I have described my invention as embodying metallic pitching pieces and metallically faced object pieces, it is obvious 105 that both the pitching and object pieces may

be made of rubber and be adapted for indoor use. Again, the object pieces may be hinged upon a pedestal so as to be movable relatively to the support for playing purposes, 5 but prevented from moving in divers directions when struck by a pitching piece.

Having thus described my invention, I claim:

1. In a game, a pitching piece, a pair of 10 independently movable object pieces, and a ground-engaging member adapted to support the object pieces; said member having such length that when the object pieces are placed thereon, the pitching piece may pass there- 15 through in one position, but cannot pass therethrough in another position, without striking one of the object pieces.
2. In a game, the combination with a support, of a pair of object pieces movably po- 20 sitioned thereon at the ends of the support, a pitching piece comprising a member having a dimension in one direction consider- ably greater than the dimension in the trans- 25 verse direction, whereby the pitching piece may pass between the object pieces in one position without striking them, but cannot

pass between the object pieces when in another position without striking them.

3. In a game, the combination with a pair of independently movable object pieces, a support therefor, a pitching piece comprising a flat disc, said object pieces being positioned on the support in such manner that the disc may pass between the object pieces when in a substantially vertical position without striking them, but cannot pass be- 30 tween the object pieces when in substan- 35 tially horizontal position without striking them.

4. In combination, a pair of object pieces, ground engaging members disposed beneath the object pieces and comprising a support therefor, said object pieces being independ- 40 ently movable on said support and pitching pieces comprising a circular disc, the ob- ject pieces being so spaced that the distance 45 between the adjacent edges thereof is less than the diameter of said disc.

In testimony whereof, I hereunto affix my signature.

WILLIAM N. JAY.
